UNITED STATES PATENT OFFICE.

JULIUS ROTHSCHILD, OF NEW YORK, N. Y.

SUSPENDERS.

SPECIFICATION forming part of Letters Patent No. 668,861, dated February 26, 1901.

Application filed September 8, 1900. Serial No. 29,372. (No model.)

To all whom it may concern:

Be it known that I, JULIUS ROTHSCHILD, a citizen of the United States, residing at the city of New York, in the county of New York and State of New York, have invented certain new and useful Improvements in Suspenders, of which the following is a specification.

My invention in suspenders relates more particularly to the means of securing the suspender-web to the buckle; and it also relates to the mechanical construction of the buckle itself, as well as to the manner in which the web is disposed about the buckle; and the objects of my invention are, first, to facilitate the means of fastening the fixed end of the suspender-web to the buckle, and, second, to shield the back of the buckle or that part of the buckle which lies in contact with the garment of the wearer, so that the garment shall come in contact with the web rather than the buckle, thereby preventing corrosion of the metallic substance of which the buckle is composed, in consequence of perspiration, and at the same time protect the garment from abrasion. These objects I attain by the construction of the buckle and the disposition of it with relation to the suspender-web, as shown in the drawings and described in the specification and more clearly pointed out in the claims.

In Figure 1 of the drawings I have shown a front elevation of my improved buckle, and in Fig. 2 a sectional view of the same, taken on the line X-X of Fig. 1. Fig. 3 is a similar view of the buckle, showing the suspender-web in position. Fig. 4 is a side elevation of my improved buckle, and Fig. 5 is a top end view of the same. Fig. 6 is a rear view of my improved buckle, showing the web in position and the manner of fastening the same to the buckle by the barbs. Fig. 7 is a plan view of a blank of which the back and lugs are formed, and Fig. 8 is a detailed view of the same when folded.

Similar characters of reference relate to the same parts in the several views.

The body 1 of the buckle is composed of a blank A, as clearly shown in Fig. 7, the two ears 2 being embossed at 3, so as to form the bearings between which the pivots 4 of the clamping-lever 5 are adapted to swing when the ears are bent up at right angles to the body

1. The blank A has barbs B punched inwardly from the back C, as shown in Figs. 3 and 6, to secure the web of fabric 6 by its end 7. The blank A is folded intermediately, so that the back C of the body 1 is doubled upon itself, so as to form a front plate D for the end 7 of the web, whereby the end 7 of the web is secured between the two plates C and D in the manner of a vise.

The front plate D is left longer than the back plate C, so that when the web of the suspender is clamped by the clamping lever or tongue 5 against the front plate D there will be a portion of it standing above the clamping lever or tongue 5, while the back plate C is made as short as possible, the object being to prevent the buckle from twisting when a strain is applied to the web 6, as shown in the drawings.

When a light web is used in the construction of the suspenders, I prefer to perforate the front plate D with perforations E, (shown in Fig. 2,) so as to register with the ends of the barbs B, which are left in this case long enough to project through the perforations E and into the web 6 when the latter is clamped by the clamping-lever 5 against the front plate D, so as to assist the buckle in holding the suspenders more firmly in an adjusted position, as shown in Fig. 2. In this instance I prefer to pierce the ears 8, as shown, in the blank A, Fig. 7, so that the pivots 4, when these ears are folded at right angles with the blank A, can pass through the same. These holes are considerably larger than the diameter of the pivots 4. With this disposition of the front plate D and the ears 8 the front plate serves the purpose of a sort of spring-jaw of a vise, and when the lighter web is used the clamping action of the tongue 5 will force the back plate C against the web, so as to cause the barbs to protrude through the web 6 and perforations E, and when the clamping lever or tongue 5 is thrown into position, so as to release the web 6, the front plate D will spring sufficiently forward in consequence of the play permitted by the perforations E in the ears 8 so as to clear that part of the web lying in contact with the surface of the front plate D, enabling the web to be adjusted up and down in the buckle without coming in contact with the sharp points of

the barbs B, projected through the web 6 and perforations E in the front plate D.

In cases where heavy web is employed for the suspenders the barbs could be left long

- 5 enough so as to get a firm grip into the material of the web without having to have them pass completely through it. I therefore construct the buckle and secure the web to the same in the manner shown in Figs. 1, 3, and 10 5, in which case the barbs are sufficiently long to pass almost through the web, but do not actually pierce it. Upon any considerable amount of strain being imposed upon the end 7 of the web, so as to exert a force 15 against the barbs B, so that they will have a tendency to bend toward the front-plate D, the front plate D will be strained, so as to be pressed forward and exert a tighter clamping 20 tendency on the suspenders where it is held by the clamping-lever 5, thereby binding the whole more firmly together.

Having fully described my invention, so that those who are versed in the art to which said invention pertains may construct and 25 use the same, what I desire to secure by Letters Patent of the United States is—

1. In suspenders, a buckle having a vise, the jaws of which are formed by the back of the buckle and a folded portion thereof, and 30 a lever for compressing the jaws, and barbs for the said vise for securing an end of the suspender-web; substantially as described.
2. In suspenders, a buckle having a vise, the jaws of which are formed by the back of the buckle and a folded portion thereof, and 35 a lever for compressing the jaws, and barbs for the said vise for securing an end of the suspender-web, said end of said suspender-web being folded about said jaws; substantially as described.

3. In suspenders, a buckle having a vise, the jaws of which are formed by the back of the buckle and a folded portion thereof, and a lever for compressing the jaws, and barbs 45 for the said vise for securing an end of the suspender-web, said end of said suspender-web being folded about said jaws, and a portion of said suspender-web being interposed between said lever and one of the said jaws 50 of the said buckle; substantially as described.

4. In suspenders having a buckle and jaws for the said buckle and a lever for compressing the jaws, a suspender-web having an end thereof interposed between the said jaws, and 55 a portion of the said web folded about the said jaws and between one of the said jaws and the said lever, said jaws having barbs for securing said end of said web; substantially as described.

5. In suspenders having a buckle and jaws for the said buckle and a lever for compressing the jaws, a suspender-web having one end thereof interposed between the jaws, and a portion of the web folded about the jaws, and 60 and between one of the jaws and the said lever, said lever being adapted to engage the web so as to clamp the same against one of

the jaws, said jaws having barbs for securing said end of the web; substantially as described.

6. A buckle having a clamping-lever, a blank folded so as to form a pair of clamping-jaws, ears folded from the fixed jaw so as to form bearing-supports for the said clamping-lever, and barbs formed from the blank; substantially as described. 70

7. A buckle, having a clamping-lever, a blank folded so as to form a vise having a fixed jaw and a yielding jaw, ears folded from the fixed jaw of said vise so as to form bearing-supports for the said clamping-lever, the said yielding jaw being greater in length than the said fixed jaw so as to project above the said fixed jaw, and barbs formed from the said fixed jaw; substantially as described. 80 85

8. A buckle, having a clamping-lever, a blank folded so as to form a vise having a fixed jaw and a yielding jaw, ears folded from the fixed jaw of said vise having recesses formed therein so as to form bearing-supports for the said clamping-lever, and ears folded from said yielding jaw having perforations through which the axis of the said clamping-lever is disposed, said yielding jaw being greater in length than the said fixed 90 95 jaw so as to project above the fixed jaw, and barbs formed from the said fixed jaw; substantially as described.

9. A buckle having a clamping-lever; said buckle being formed of a folded blank, said blank folded so as to form a vise having a fixed jaw and a yielding jaw, ears folded from the fixed jaw having recesses formed therein, so as to form bearings for the said clamping-lever, ears also folded from the yielding jaw having perforations through which the axis of the clamping-lever is disposed, said yielding jaw being greater in length than the fixed jaw, whereby the same projects above the plane of the said bearing-support and the end of the fixed jaw; substantially as described. 100 105 110

10. A buckle, having a clamping-lever, a blank folded so as to form a vise having jaws, and ears folded from the jaws of said vise having recesses formed therein so as to form 115 bearings for the said clamping-lever, said clamping-lever being adapted to compress a material between the jaw adjacent to the clamping end of the said lever and the said lever, the other jaw being adapted to clamp 120 a material against the second jaw, the said jaw adjacent to the said clamping-lever being greater in length than the other said jaw; substantially as described.

11. In suspenders, a buckle having a pivoted clamping lever or tongue, said buckle being formed of a blank folded so as to form a vise having a fixed jaw and a yielding jaw, and ears folded from the fixed jaw of the vise, said ears having recesses so as to form 125 130 bearing-supports for the pivots of the clamping lever or tongue of the buckle and ears folded from the yielding jaw having perforations through which the said pivots of the

said clamping lever or tongue pass, said yielding jaw being greater in length than the fixed jaw, barbs for the vise for securing an end of the suspender-web being interposed between the jaws, and a free portion of said suspender-web being folded about the jaws and between the said yielding jaw and the said lever, said lever being adapted to compress the said free portion of the suspender-web, between the yielding jaw and the said tongue the end of the suspender-web being compressed between the yielding jaw and the fixed jaw, and upon the said compression by the said clamping lever or tongue, the said yielding jaw will be restrained by the pivots of the said clamping lever or tongue in the said perforations in the ears of the yielding jaw, and upon the release of the web by the said tongue, the said yielding jaw upon being released and by virtue of the elasticity of the said web compression will again be restrained by the pivots of the said clamping lever or tongue in the perforations of the ears of the yielding jaw; substantially as described.

25 12. In suspenders, a buckle having a vise, the jaws of which are formed by the back of the buckle and a folded portion thereof, a lever for compressing the jaws, and barbs for one of the jaws and recesses for the other

jaw adapted to register with the said barbs; 30 substantially as described.

13. In suspenders, a buckle having a vise, the jaws of which are formed by the back of the buckle and a folded portion thereof, a lever for compressing the jaws, and barbs for 35 one of the jaws and recesses for the other jaw, for securing an end of the suspender-web, said end of the said suspender-web being folded about said jaws and said barbs passing through the same and registering with the 40 said recesses; substantially as described.

14. A suspender-buckle consisting of a blank folded so as to form a vise having a fixed jaw and a yielding jaw, a lever for compressing the jaws, and barbs on the fixed jaw 45 and recesses in the yielding jaw for securing an end of the suspender-web, said end of the suspender-web being folded about the said jaws and said barbs passing through the same and registering with the said recesses; 50 substantially as described.

In testimony whereof I have signed my name to this specification in the presence of two subscribing witnesses.
